THREAD GUIDE DRIVING ARRANGEMENT
FOR TEXTILE MACHINES, ESPECIALLY
FOR ARTIFICIAL SILKOtto Bochmann, Remscheid-Lennep, Rhineland,
Germany, assignor to Barmer Maschinen-
fabrik Aktiengesellschaft, Wuppertal - Ober-
barmen, GermanyApplication May 3, 1940, Serial No. 333,162
In Germany February 14, 1939

4 Claims. (Cl. 242—158)

For the driving of the thread guides on textile machines, that is for the transmission of the movement of the curve upon the thread guides or thread guide bars for the obtention of the reciprocating movement hinges are necessary in most instances. Such hinges have, however, a certain inconvenience. The more hinges exist in the transmission elements the clearance becomes greater this having evidently an unfavorable effect upon the reversing movement of the thread guides. Bobbins are thus produced the winding of which is not always perfect according to the required thread guide movement. Hinge arrangements result further in that, especially at the reversing points of the thread guide, a certain unrest occurs as these hinges do not exert a damping effect, but fully transmit upon the thread guide the shock produced by the curve at the return movement. This evidently also unfavorably influences the thread laying. This is especially prejudicial when high changing speeds occur, the more so as it is then necessary to make as small as possible the masses to be moved, which means that the thread guide rods must be as light as possible. In the case of thread guide arrangements on artificial silk spinning machines other inconveniences occur when hinges are employed, for instance, that hinge points which are above the acid bath wear rapidly. It is further a great inconvenience to have hinge points above the acid bath which have to be lubricated continually. In the latter instance it easily happens that the bobbins to be wound are soiled, and the oil can easily come into contact with the acid bath so that the bath is useless.

In order to avoid all these inconveniences the hinges necessary for the transmission of the reciprocating movement are made, according to the invention, of hingeless elastic connections. For instance rubber or other elastic artificial masses or textiles may be used as connections. Between the mutually movable elements a corresponding elastic plate is preferably arranged, for instance a plate of rubber, which at both ends is connected with the elements by clamping.

By this construction it is attained that direct hinges are avoided and the movability is greater than before. Not only the advantage of perfect freeness from clearance is thus obtained, but such hingeless connections exert also a damping effect, so that, particularly at the reversing points of the thread guides, the shocks caused by the curve are intercepted in the hingeless connection. By this arrangement an absolutely quiet reciprocating movement of the thread guides is obtained,

so that, even if the thread guide rods and other elements are of lighter construction in order to attain high spinning- and changing speeds, any unrest in the thread guide movement is securely avoided. There exists further the advantage that, when such connections are employed in artificial silk spinning machines, these connections can no longer be corroded by the acid bath and that no lubricating is necessary. Consequently, there exists no longer the danger of soiling for the material or for the acid bath. According to the invention it is possible to obtain, even at the highest spinning speeds, a perfect thread laying and thereby a correspondingly good winding of the bobbin.

5 An embodiment of the invention is illustrated by way of example in the only figure of the accompanying drawing which shows this arrangement diagrammatically on a spinning machine for artificial silk.

10 In the example shown, the winding of the bobbin 1 is effected by a thread guide lever 2, which is connected with a bar 3 by a hingeless connection 4. In this instance a rubber plate is used, which is clamped at one end in the bar 3 and at the other end in the thread guide lever 2 and thus permits a movement of the thread guide lever. A changing rod 5 acts upon the thread guide lever 2 and is connected with this lever by 15 an elastic element 6. In the present case two hinge points are necessary for the reciprocating movement of the thread guide, these hinge points being replaced according to the invention by hingeless connections.

20 35 I claim:

1. A thread guide driving arrangement for textile machines, especially for artificial silk, comprising a thread guide, and elastic hinge connections for the thread guide operative for the 25 shockless transmission of reciprocatory movements upon the thread guide, the elastic hinge connections being made of rubber.

2. A thread guide driving arrangement for textile machines, especially for artificial silk, comprising a thread guide, an elastic hinge connection forming a pivot support for the thread guide and means for oscillating the thread guide operative for the shockless transmission of reciprocatory movements upon the thread guide.

3. A thread guide driving arrangement for textile machines, especially for artificial silk, comprising a thread guide, and elastic hinge connections for the thread guide operative for the shockless transmission of reciprocatory movements upon the thread guide, the thread guide

including a lever and a fixed bar adjacent one end of the lever, and the elastic hinge connections including a rubber plate having clamping support at its ends on the thread guide lever and bar.

4. A thread guide driving arrangement for textile machines, especially for artificial silk, comprising a thread guide, and elastic hinge connections for the thread guide operative for the shockless transmission of reciprocatory move-

ments upon the thread guide, the thread guide comprising a lever and changing rod, one of said elastic hinge connections providing means for attaching the changing rod to the thread guide lever intermediate the ends of the latter, and the other elastic hinge connection comprising a rubber plate having one end fixed to the thread guide lever and a fixed bar to which the other end of the rubber plate is attached.

10

OTTO BOCHMANN.
